[57] CLAIM

The ornamental design for a convertible seat or similar article, substantially as shown and described.

DESCRIPTION

FIG. 1 is a perspective view of a convertible seat or similar article showing my new design, with the arm rests disposed intermediate the ends thereof; thus, providing a three individual chair seat configuration, and the figure further shows the right end view wherein the left end view is a mirror image thereof.

FIG. 2 is a perspective view thereof with one of the arm rests disposed adjacent the end thereof; thus, providing a chair and love seat configuration; and

FIG. 3 is a perspective view thereof with both arm rests disposed adjacent the ends; thus, providing a sofa configuration.

The rear of the seat is plain and unornamented.
